IGNITION ANALYZER

Edwin L. Schwartz, Los Angeles, Calif., assignor to
Rite Autotronics Corporation

Filed Nov. 6, 1974, Ser. No. 521,364

Term of patent 14 years

Int. Cl. D10—04

U.S. Cl. D10—78

Fig. 1.

Fig. 2.

Fig. 3.

Fig. 4.

Fig. 5.

Fig. 6.

Fig. 7.

FIG. 1 is a front elevational view of an ignition analyzer showing my new design;

FIG. 2 is a top plan view;

FIG. 3 is a bottom plan view;

FIG. 4 is a right side elevational view, the left side being a mirror image thereto;

FIG. 5 is a rear elevational view;

FIG. 6 is a right front perspective view with the handle opened to the sitting position; and

FIG. 7 is a right front perspective with the handle in the fully extended position.

I claim:

The ornamental design for an ignition analyzer, substantially as shown and described.
